PASTING MECHANISM FOR STITCHING MACHINES

Oscar Kleinschmit and Oskar Müller, Leipzig-Plagwitz, Germany, assignors to Gebrüder Brehmer, Leipzig-Plagwitz, Germany, a German company

Application July 26, 1930, Serial No. 471,056,
and in Germany May 30, 1930

16 Claims. (Cl. 91—47)

This invention relates to blade stitching machines for books and more particularly concerns the mechanism by means of which paste can be applied in the form of a strip at a point close to the folded edge of the book signature.

The object of this invention is to provide means for supplying paste evenly to the paste applying member and to enable the latter to apply a paste strip to the lateral edge of a folded sheet while

10 the latter is positioned for stitching.

According to this invention we provide mechanism wherein the adhesive-applying part is caused to contact momentarily with an adhesive-supply roll in travelling to its operative position.

15 One embodiment of the invention is shown in the accompanying drawings, in which:

Figure 1 is a side elevation of a book stitching machine showing the paste applying mechanism at rest.

20 Figure 2 shows the mechanism in its initial operative position.

Figure 3 illustrates the position of the mechanism when the paste strip is about to be applied to the sheet edge, while

25 Figure 4 is an enlarged detail view of the actual paste applying members.

Journalled in the left and right hand frames of the machine 1 is a main driving shaft 2 upon which are mounted eccentrics or cams 3 and 4.

30 The cam 3 is adapted to actuate the blade lever 5 and the cam 4 is employed for operating a bell crank lever 6, one arm of which forms a toothed segment lever 6a. Both of these levers are mounted on a shaft 7 which is also journalled in the side frames of the machine.

35 The follower roller 6b, mounted upon the second arm of the lever 6, is held in engagement with the cam 4 by means of a tension spring 28, the other end of which is secured to a member 28a attached to the

40 main frame. The saddle or table 8 is mounted on the blade lever 5. A paste applying member 9 rigidly connected to a control lever 10, which extends from one side thereof and carries a roller 10a at its lower extremity, is journalled in levers 11 which are rigidly connected to the toothed segment 13 through the shaft 12.

45 A tension spring 24 anchored at one end to the lever 11 and at its other end to the paster blade 9 is adapted to pull the latter about its pivot either into the inoperative or final operative position (Figures 1 and 4) or to the initial operative position (Fig. 2) when the lever 10 is tripped as hereinafter described. These positions of the paster blade are predetermined by means of one 50 of a pair of lugs 25, 26 formed integral with the

control lever 10, which lug is caused to abut against a stop 27 provided on the lever 11, thus limiting the rotation of the paster blade 9 and control lever 10 about their common axis. A curved guide 14 is secured on the blade lever 5 and 60 is adapted to engage the follower roller carried at the end of the lever 10 and thereby to guide the latter together with the paster 9 into the sheet pasting position.

A pawl 15, mounted on one of the levers 11, 65 is adapted to engage a ratchet wheel 17 rigidly mounted on the spindle of a paster roller 18 and thereby to rotate the latter as the lever 11 carrying the paster 9 is swung inwards during the rotation of the cam 3. Journalled on the lever 70 5 is a two armed locking lever 19, one downwardly extending arm 19a of which is adapted during the inoperative position of the mechanism to engage a lug 20 formed on the lever 6 and to be held in engagement therewith by 75 means of a tension spring 19b which is secured at one end to the second horizontally extending arm of the lever 19 and at the other end to the lever 6a. A bell crank lever 21, carrying a follower roller 21a at its lower extremity, is pivotally mounted upon the lever 6a and forms the means for tripping the paster 9 into its initial position when the roller 21a is engaged by the extension 22b of the lever 22. A tension spring 80 21b is secured between the main frame and the 85 lever 21 in order to keep the follower roller 21a in contact with the member 22b. The tripping lever 21 and the locking lever 19 are adapted to be actuated simultaneously by a throw-in lever 22 which is journalled in the side frame 1 90 of the machine and preferably operated by means of a foot treadle 22a.

The operation of the pasting mechanism is as follows:—

For ordinary stitching operations the signature 95 23 to be stitched is placed on the saddle table and the machine is operated by the depression of a pedal 29, thus causing stitching of the signature in a known manner. If a signature is to be strip-pasted the operation is 100 repeated as above but in addition to the pedal 29, the pedal-shaped end 22a at the lower extremity of the throw-in lever 22 by which the pasting device is controlled must also be depressed. By depressing the lever 22 the lever 21 is actuated, 105 through the extension 22b and follower 21a, and in turn trips the control lever 10 and the spring controlled paster 9 secured thereto (Figure 2). At the same time the locking lever 19 is also released by the throw-in lever 22 through 110

the arm 19a engaging with the lever 22 whereby the toothed segment lever 6a is freed and is rocked by the tension spring 28 in accordance with the curve on the cam 4. The cams continue to rotate in the direction of the arrow with the result that the levers 11 together with the parts mounted hereon travel in upward direction through the engagement of the toothed members 6a and 13. The pawl 15 moving in an arcuate path engages with the ratchet wheel 17 thus rotating the paste roller 18 mounted on the same shaft and so causing that part of the paste roller upon which the paster 9 is about to bear to be supplied with fresh paste. By this arrangement the paster 9 is moved at the same speed as that at which the paste roller is rotated. It does not therefore wipe or scrape the paste roller but performs a rolling action when in contact thereon thereby preventing the formation of lumps and drops of paste on the blade. In its continued movement in the upward direction the roller 10a of the control lever 10 travels along the curved guide 14 thereby rotating the paster about its axis until the paster 9 is in contact 25 with the signature in order to apply a strip of paste thereto.

The levers 11 then immediately commence to move again downwardly, (Fig. 3). During the latter part of this motion the blade lever 5 commences to move in upward direction thereby bringing the signature located on the table to the stitching mechanism where it is stitched in known manner. By means of this novel device paste can be applied to every sheet but as is usual only the first and the second and the last but one and the last sheets can be connected by a strip of paste.

What we claim is:—

1. In a stitching machine mechanism for the purpose of applying adhesive to the edge of a folded sheet, an adhesive-supply roller, a spring-held adhesive-applying member, pivoted arms rotatably supporting said adhesive-applying member, means for actuating said supporting arms, means for actuating said supply roller, means for tripping said adhesive-applying member into one of two positions, means for operating said tripping means, means for locking the said supporting arms against movement and means for tripping said locking means.

2. In a stitching machine as claimed in claim 1, means for controlling the operation of said adhesive applying mechanism comprising a foot pedal adapted to engage and trip said locking means and indirectly to trip said adhesive applying member.

3. In a stitching machine mechanism for applying adhesive to the edge of a folded sheet, in combination, an adhesive-supply roller, a ratchet wheel mounted on said roller, a spring-held adhesive-applying member, pivotal arms rotatably supporting said adhesive-applying member, a ratchet-pawl mounted on said supporting arms and adapted to engage said ratchet wheel, means for actuating said supporting arms, means for locking said actuating means against movement, means for rocking said adhesive-applying member about its axis, a foot pedal for controlling said locking means and tripping said adhesive-applying member, and guiding means for guiding the said adhesive applying member into its final operative position during its travel to the said folded sheet.

4. In a stitching machine, mechanism for the purpose of applying adhesive to the edge of a

folded sheet, comprising an adhesive-supply member, an adhesive-applying member, means for lifting the adhesive-applying member upwardly into contact with the folded sheet, and means for engaging the said adhesive-applying member with the adhesive-supply member during the upward travel of the said adhesive-applying member.

5. In a stitching machine, mechanism for the purpose of applying adhesive to the edge of a folded sheet, comprising an adhesive-supply member, an adhesive-applying member, means for moving the adhesive-applying member towards the folded sheet, means for contacting the said adhesive-applying member with the edge of the folded sheet, means for contacting the face of said adhesive-supply member with the face of said adhesive-applying member during the travel of the adhesive-applying member towards the folded sheet, and means for moving the face of the adhesive-supply member concurrently with and at the same speed as the adhesive-applying member during contact of said faces to avoid relative sliding movement between the faces.

6. In a stitching machine, mechanism for applying adhesive to the edge of a folded sheet, comprising an adhesive-container, an adhesive-supply roller rotatably mounted in the said container, a ratchet wheel mounted on the said roller, a spring-held adhesive-applying blade, pivotal arms rotatably supporting said adhesive-applying blade, a ratchet-pawl mounted on said supporting arms and adapted to engage said ratchet wheel, means for actuating said supporting arms, means for locking said actuating means against movement, means for rocking said adhesive-applying blade about its axis, a foot pedal for controlling said locking means and rocking said adhesive-applying blade, and means for contacting the said adhesive-applying blade with the requisite edge of the folded sheet.

7. In a book-stitching machine, means for applying adhesive to a folded sheet, comprising a swinging sheet carrier, an adhesive-supply member positioned beneath said sheet carrier, an adhesive-applying member adapted to rest beneath said sheet carrier, means for positioning said adhesive-applying member to contact with said adhesive-supply member, and means for swinging said adhesive-applying member upwards into the path of travel of said sheet carrier to contact with a folded sheet carried by said sheet carrier.

8. In a book-stitching machine, means for applying adhesive to the fold edge of a folded sheet, comprising a pivotal sheet carrier, an adhesive-supply member positioned beneath said sheet carrier, an adhesive-applying member adapted to rest beneath said sheet carrier, means for contacting said adhesive applying member with said adhesive-supply member, and means for swinging said adhesive-applying member upwards into the path of travel of said sheet carrier to contact with the fold edge of a sheet carried by said sheet carrier.

9. In a stitching machine, means for applying adhesive to the fold edge of a folded sheet, comprising a pivotal sheet carrier, an adhesive-supply member, an adhesive-applying member, means for contacting said adhesive-applying member with said adhesive-supply member, means for swinging said adhesive-applying member into the path of travel of said sheet-carrier, and guide means mounted upon said sheet carrier to guide the said adhesive-applying mem-

- ber into contact with the fold edge of a folded sheet carried by the said carrier.

10. In a stitching machine, adhesive-applying means comprising a rotatable adhesive-supply roller, a ratchet wheel carried by said roller, a movable adhesive-applying member, means for contacting said adhesive-applying member with said adhesive-supply roller, and a pawl carried by said adhesive-applying member and adapted to engage said ratchet wheel thus to rotate said adhesive-applying roller so that the latter contacts with said adhesive-applying member during contacting movement thereof with simple rolling movement between the contacting surfaces. 80

11. In a stitching machine provided with a pivotal sheet carrier, means for applying adhesive to a sheet carried by the sheet carrier, comprising an adhesive supply roller, a movable adhesive-applying part, means for contacting said adhesive-applying part during movement thereof with said adhesive-supply roller, and means for imparting movement to said roller during the contact thereof with said adhesive-applying part so that the contacting surfaces come together and part with simple rolling movement. 90

12. In a stitching machine provided with a moving sheet carrier, adhesive-applying means comprising an adhesive-supply member, an adhesive-applying member adapted to assume either of two positions, means for tripping said adhesive-applying member into one of said positions to contact with said adhesive-supply roller, means for moving said adhesive-applying member into the path of travel of the movable sheet carrier, and guide means mounted on said carrier to guide said adhesive-applying member into the second of the beforementioned positions therein to contact with a sheet carried by said sheet carrier. 100

13. In a stitching machine, means for applying adhesive to a folded sheet, comprising an adhesive-supply member, an adhesive-applying member, means for contacting said adhesive-applying member with said adhesive-supply member, means for swinging said adhesive-applying member towards the folded sheet to which adhesive is to be applied, and means for imparting a secondary movement to said adhesive-applying member whereby it is positioned to contact with said sheet during the swinging movement referred to. 110

14. In a stitching machine, means for applying adhesive to the edge of a folded sheet, comprising an adhesive-supply member, a pivotal adhesive-applying member, means for lifting said adhesive-applying member upwardly towards the folded sheet, means for tripping said adhesive-applying member about its pivot to contact with said adhesive-supply member, and means for imparting a further rotary movement to said adhesive-applying member during its upward movement to position this member in the operative position to contact with said folded sheet. 120

15. In a stitching machine, in combination, a machine drive, a sheet carrier mounted on pivotal arms, an adhesive-container positioned below said sheet carrier, an adhesive-supply member associated with said adhesive-container, an adhesive-applying member adapted to rest below said sheet carrier and supported by pivotal arms, means for pivoting said second pivotal arms to brackets secured to said sheet carrier, a curved guide strip mounted on one of said first pivotal arms, means for oscillating from said machine drive said first pivotal arms and sheet carrier mounted thereon, and means for oscillating from said machine drive said second-mentioned pivotal arms so that the said adhesive-applying member is caused first to contact with said adhesive-supply member and then to engage said curved guide strip thereby to be guided into contact with a sheet carried by said sheet carrier. 130

16. In a stitching machine, in combination, a machine frame, a drive shaft, cam driving means mounted on said shaft, sheet carrier arms pivoted to said machine frame, a sheet carrier mounted on the free extremities of said arms, a curved guiding strip mounted on one of said arms, a bracket depending from said arms, curved arms pivoted to said bracket, an adhesive-applying bar rotatably mounted in the free extremities of said curved arms and spring held in either of two positions, an adhesive-supply roller, means for oscillating said sheet carrier arms and sheet carrier from said cam driving means, means for tripping said adhesive-applying member into position for contacting with said adhesive-supply roller and means for moving said curved arms upwards about their pivots so that the said adhesive-applying member is contacted with said adhesive-supply roller and then engaged with said curved guiding strip and rotated to its second operative position to contact with a folded sheet carried by said sheet carrier. 140
